UNITED STATES PATENT OFFICE

148,256

DESIGN FOR A CIGARETTE SNUFFER

Otto E. Sovereign, Bay City, Mich.

Application August 24, 1946, Serial No. 132,833

Term of patent 14 years

(Cl. D85—2)

To all whom it may concern:

Be it known that I, Otto E. Sovereign, a citizen of the United States of America, residing at Bay City, in the county of Bay and State of Michigan, have invented a new, original, and ornamental Design for Cigarette Snuffers, of which the following is a specification, reference being had to the accompanying drawing, forming part thereof.

In the drawing:

Fig. 1 is a top plan view of a cigarette snuffer, showing my new design.

Fig. 2 is a side-elevational view thereof, and

Fig. 3 is a perspective view thereof.

I claim:

The ornamental design for a cigarette snuffer, as shown.

OTTO E. SOVEREIGN.
